PATENTED AUG 9 1870

Samuel J. Bent

Design for the top plates-mangers.

Fig. 2.

United States Patent Office.

SAMUEL S. BENT, OF PORT CHESTER, NEW YORK.

Design No. 4,275, dated August 9, 1870.

DESIGN FOR TOP PLATE FOR MANGERS.

The Schedule referred to in these Letters Patent and making part of the same

To all whom it may concern:

Be it known that I, SAMUEL S. BENT, of Port Chester, in the county of Westchester and State of New York, have invented or produced a Design for the Top Plates of Mangers, and the following is hereby declared to be a full and correct description thereof.

This design does not relate to the general outline of a top plate for mangers, but to the sectional shape of that portion of the plate which binds or covers the top edges of the manger.

In the drawing I have represented in Figure 1 a plan of a top plate adapted to a corner manger, and, in this character of manger, I prefer to make only that portion of the plate marked *a* of the sectional shape forming the subject of my design.

In Figure 2, which is a section at the line *x x*, fig. 1, the plate is shown in about full size, to represent the sectional shape more clearly.

I make the front edge *a'* of the plate as a roll or segment of a cylinder, from the point *b* to its junction with the horizontal or flat portion *c* of the plate, said rounded portion projecting partially above the

flat portion, and joined to it by a curve of about the radius shown.

The back edge of the plate I round, as at *e*, from the portion *c* to the point *h*, and the lower surface of the plate between the points *h b* I form of the recessed shape shown, to receive and cover the top flange of a metal manger, or the planking, when the manger is made of wood.

This top plate is neat in appearance, and it covers up the top edge of the manger, and there are no angles to injure the horse if he rubs his head or neck against the plate, and, in consequence of the rounded edges, the horse can obtain no hold on the plate if he endeavors to bite the same.

I claim—

The design of the sectional shape and configuration of the top plate for a manger, as shown.

Dated this 3d day of June, A. D. 1870.

SAMUEL S. BENT.
